LOOSE LEAF BOOK BINDING MECHANISM

Filed June 2, 1928

UNITED STATES PATENT OFFICE

FRED N. LANG, OF CHICAGO, ILLINOIS

LOOSE-LEAF BOOK-BINDING MECHANISM

Application filed June 2, 1928. Serial No. 282,392.

This invention relates to improvements in loose leaf books.

The general object of the invention is to provide a loose leaf book wherein the binding 5 ring mechanism is secured to the binding in a novel manner.

A specific object of the invention is to provide a loose leaf book having a stiff binding edge wherein the binding ring mechanism is 10 positioned in a recess therein.

Another object of the invention is to provide a loose leaf book wherein the base of the separable rings is positioned below the surface of the covers when the covers are opened 15 whereupon only the active leaf-holding portions of the rings project above the surface of the covers when they are opened.

A further object of the invention is to provide a novel hinge construction for securing 20 the covers of the book to the binding.

Other objects and advantages of this invention will be apparent from the following description taken in connection with the accompanying drawings wherein:

25 Fig. 1 is a perspective view of my improved loose leaf book.

Fig. 2 is an enlarged fragmentary interior face view of my device with the covers opened.

30 Fig. 3 is a section taken on line 3—3 of Fig. 2.

Fig. 4 is a section taken on line 4—4 of Fig. 2.

Fig. 5 is a detail perspective view of the 35 binding block.

Fig. 6 is an enlarged fragmentary section showing the hinge operatively positioned on the binding block and

40 Fig. 7 is a perspective view of my improved hinge construction.

Referring to the drawings by reference characters I have indicated my improved loose leaf book generally at 10. As shown, this device comprises a binding block 12 having covers 14 secured thereto by hinges indicated generally at 15.

The binding block 12 is preferably made of wood and provided with a trough 16 in which a metal binder ring mechanism 17 is 45 adapted to be positioned. The binding block

12 may be shaped from metal or made from any other suitable material other than wood such as stated.

The binder ring mechanism may be of any desired type and includes split binder rings 18 and end tongues 19. After the binder ring mechanism 17 is positioned in the trough 16 of the block 12 retaining blocks 20 are positioned in the trough 16 over the lips 19 of the ring mechanism 17. The blocks 20 may 55 be nailed to the block 12 or secured thereto in any other desired manner such as by gluing it thereto as shown.

Adjacent each of the binder rings 18 and on either side thereof notches 22 are provided 60 in the block 12 to allow for the opening of the rings to the position shown in dotted lines in Fig. 3.

The hinge 15 comprises two strips of cloth-like material 23 and 24 stitched together as 70 indicated at 25 to form portions 26, 27, 28 and 29, as clearly shown in Fig. 7.

When a hinge 15 is placed on the block 12 the portion 28 is glued to the top face of the block, the portion 26 to the adjacent side of 75 the block and then the portions 27 and 29 are glued to the cover, one on either side as clearly shown in Figs. 3 and 6. The pivoting action of the hinge comes on the stitching 25 which prevents the hinge material from 80 cracking and pulling apart.

A strip of paper or some similar material 31 may be glued to the interior of the cover and over the edges of the interior hinge portion 29 and the entire interior of the cover 85 may be further covered if desired and the blocks 20 may be covered with a strip of material similar to the hinge material which is glued to the retaining block 20 and the block 12 before the hinges are placed thereon as indicated at 32.

The entire exterior of the covers 14 and the block 12 are preferably covered with an imitation leather or some similar material as indicated at 34.

90 A loose leaf book constructed in accordance with my invention is very rigid and durable owing to the binding block 12 which prevents wobbling of the book and the hinge 15 which, owing to its novel construction, is 100

very strong and securely holds the covers to secured to the side of said binding block and the other two portions being secured to one of said covers, one on either side thereof.

From the foregoing description it will be apparent that I have provided a novel form 5 of loose leaf book which is simple in construction, rigid and durable.

Having thus described my invention, I claim:

1. In a device of the class described, a 10 binding block having a trough extending the full length of the same, a binder ring mechanism, said ring mechanism including a body having a plurality of split rings, said body having a tongue at each end thereof, 15 said ring mechanism being positioned in said binding block trough and a retaining block in each end of said trough and engaging said tongues.

2. In a book, a binding member, a cover 20 adjacent said binding member, a hinge adapted to secure said cover to said binding member, said hinge comprising two strips of flexible material sewed together on a line intermediate their edges, to form four portions, 25 one of said hinge portions being secured to the top face of said binding member, another of said hinge portions being secured to the side of said binding member and the other two portions being secured to said cover, one 30 on either side thereof.

3. In a device of the class described, a 35 binding block, a cover adjacent each side of said binding block, hinges adapted to secure each of said covers to said binding block, each of said hinges comprising two strips of flexible material sewed together on a line intermediate their edges, to form four portions, one of said hinge portions being secured to the top face of said binding block, 40 another of said hinge portions being secured to the side of said binding block and the other two portions being secured to one of said covers, one on either side thereof.

4. In a device of the class described, a 45 binding block having a trough extending the full length of the same, a binder ring mechanism, said ring mechanism including a body having a plurality of split rings and having a tongue at each end of the body, said ring 50 mechanism being positioned in said binding block trough, a retaining block positioned in said binding block trough adjacent each end thereof and over said ring mechanism tongues, said retaining blocks being secured to said binding block, said binding block having notches therein adjacent each of said 55 rings to allow said rings to open, a cover adjacent each side of said binding block, hinges adapted to secure each of said covers to said binding block, each of said hinges comprising two strips of flexible material sewed together on a line intermediate their edges to form 60 four portions, one of said hinge portions being secured to the top face of said binding block, another of said hinge portions being

In testimony whereof, I hereunto affix my signature.
